UNITED STATES PATENT OFFICE.

ANTHONY COSTA, OF CLEVELAND, OHIO, ASSIGNOR TO THE GRAVITY CARBURETER COMPANY, OF CLEVELAND, OHIO, A CORPORATION OF OHIO.

CARBURETER.

1,233,287.

Specification of Letters Patent. Patented July 10, 1917.

Substitute for application Serial No. 765,322, filed May 3, 1913. This application filed August 24, 1915. Serial No. 47,050.

To all whom it may concern:

Be it known that I, ANTHONY COSTA, a citizen of the United States, and a resident of Cleveland, county of Cuyahoga, and State of Ohio, have invented a new and useful Improvement in Carbureters, of which the following is a specification, the principle of the invention being herein explained and the best mode in which I have contemplated applying that principle, so as to distinguish it from other inventions.

My invention relates to improvements in carbureters, and pertains more particularly to carbureters for using heavy oil, such as kerosene, etc.

The object of my invention is to provide a carbureter in which gasoline is used in starting the engine and in which the gasoline supply is automatically cut off and kerosene used and in which the stopping of the engine automatically allows another charge of gasoline to flow to the carbureter to start the engine.

Another object of my invention is to provide means whereby with the aid of the exhaust of the engine a perfect combustible mixture of kerosene and air may be obtained and thus greatly increasing the power of the engine and at the same time decreasing the cost of fuel consumed by the engine.

A still further object of my invention is to provide a simple, cheap and more effective carbureter of this character having certain details of structure hereinafter more fully described.

In the accompanying drawings:

Figure 1 is a longitudinal vertical sectional view of a carbureter embodying my invention.

40 Fig. 2 is a side elevation showing the carbureter applied to an internal combustion engine.

Fig. 3 is a perspective view of my improved carbureter, showing the explosive mixture passing through the exhaust manifold for heating the same before passing to the intake manifold.

Fig. 4 is a perspective view of the carbureter showing the butterfly valve operating means.

Fig. 5 is a perspective view partly in section and partly broken away of the oil supply tube in the mixing chamber and showing the nozzle cap removed.

Fig. 6 is a bottom plan view of the kerosene float and valve operating means.

Fig. 7 is a vertical longitudinal sectional view similar to Fig. 1, showing the maintained oil level receptacle, the mixing chamber and the air-intake surrounded by a water-jacket and in communication with the water-jacket of the engine.

Referring now to the drawings, 1 represents the oil-receptacle having a base 2 formed of a casting and its side-walls 3 of glass, in order that the oil-level may be at any time determined. The base 2 is provided at the center with a central auxiliary chamber 4, having a pipe 5 in communication with its lower end, by means of which gasoline is permitted to pass into the said receptacle. Within this chamber 4 is a float 6, having its lower end connected to a link 7. The lower end of the link is pivotally connected to the intermediately pivoted lever 8, and the outer free end of said lever carrying a valve 9, closing the opening 10 communicating with the gasoline-supply pipe 5. The upper end of the oil-tank is closed by a cover 11, and is held thereon in any desired manner. The cover 11 is provided with a central opening 12, in which is screw-threaded a pipe connection 13, which leads upwardly and is connected to the intake manifold 14 at 15, as clearly shown in Fig. 2 of the drawings. The pipe connection 13 is provided with an enlarged bore 16 communicating with the auxiliary chamber 4. The upper end of the bore is provided with a valve-seat 17, upon which the ball-valve 18 rests and closes the communication between the auxiliary-chamber 4 and the pipe leading to the intake-manifold. The lower end of the bore 16 is screw-threaded and has a ring 19 screwed therein to form a stop to limit the downward movement of the ball 18. Connected to the lower end of the ball 18 is a coiled spring 19, which has its lower end connected to a link 20, the said link being pivotally connected to the upper end of the float 6, within the auxiliary chamber 4.

By this structure it will be seen that the suction in the intake-manifold 14, causes the ball 18 to seat itself upon the seat 17 and close the communication between the intake-manifold and the auxiliary chamber.

The upward movement of the ball 18, by

the suction of the engine, raises the float 6 whereupon through the medium of the link 7 and the lever 8, the valve 9 closes the communication 10 and shuts off the supply of 5 gasolene to the auxiliary chamber 4.

The kerosene chamber 21 surrounds the gasolene chamber 4 and the casting 2 has an opening 22 communicating with a nipple 23 by means of which the kerosene oil-supply 10 pipe is connected thereto. A float 24 of a circular ring-like form is located in the kerosene chamber and is provided with two downwardly extending lugs 25 and 26 to which is loosely connected the yoke 27, said 15 yoke being intermediately pivoted at 28 to a stud 29 carried by the casting 2. The outer free end of the yoke 27 has pivotally carried thereby a valve 30, which closes the communication 22 of the kerosene supply 20 whereby a pre-determined oil level is maintained within the kerosene receptacle.

The casting 2 has formed integral therewith an extension 31, which terminates in a cylindrical upwardly disposed mixing 25 chamber 32. The chamber 32 is provided with an upwardly extending oil nozzle 33, which has two vertically disposed oil passages 34 and 35, the passage 34 representing the gasolene supply and the passage 35 represents the kerosene supply. The lower end of the kerosene passage 35 is in communication with a lateral passage 36, which extends through the casting 2 and is in communication with the kerosene chamber 21. 30 The gasolene passage 34 likewise has an extension 37 which extends through the casting 2 and is in communication with the central gasolene chamber 4, as clearly shown in Figs. 1 and 5 of the drawings.

40 The oil nozzle 33, as shown in Fig. 1, of the drawing, extends upwardly about midway the height of the mixing chamber and the oil passage 35 has a contracted upper end 38, forming a seat 39 for the valve 40. 45 The valve 40 extends downwardly through the passage and has a screw-threaded portion 41, screwed within the nipple 42 formed as a part of the casting 2. The lower end of the stem below the nipple is provided 50 with an operating handle 43 and a lock-nut 44, by means of which the valve-stem may be positively locked in its adjusted position to prevent the jar to which the carburetor is subjected from working the valve-stem in 55 either direction. The upper end of the oil-nozzle 33, as shown in Fig. 5 of the drawings, is preferably flat and a cap 46 tightly fits over and around the upper end of the nozzle leaving a space 37 between the upper 60 end of the nozzle and the cap. The nozzle is provided with a central oil-discharge opening 48, for discharging either kerosene or gasolene therefrom. This opening 48 is of a diameter less than that of either of the 65 openings 34 and 35. The nozzle 46 has its

upper end beveled, as indicated at 49, which allows the air to pass inwardly close to the discharge opening 48, as will be hereinafter more fully described.

Within the mixing chamber 32 is a mixing tube 50, which is spaced from the walls of the mixing chamber and held in this spaced position by means of the webs 51, as shown in Fig. 1 of the drawings. The mixing tube starts at a point considerably above 70 the bottom of the mixing chamber and has an inwardly curved portion 53 in a horizontal alignment with the upper end of the nozzle 46. This inwardly drawn portion forms a contracted opening surrounding the 80 beveled walls 49 of the nozzle 46. The mixing tube above the flange is again flared outwardly and extends vertically to a point adjacent the upper end of the mixing chamber. This vertical portion 54 of the mixing tube is provided with a great number of 85 perforations 55, which slant upwardly from the outer surface and entirely surround the mixing tube. The mixing chamber 32 is drawn inwardly at a point in horizontal 90 alignment with the upper end of the vertical portion of the mixing tube and is provided with an inwardly beveled portion 57, terminating in an outwardly beveled portion 58, which ends at the extreme upper 95 end of the mixing chamber. The inwardly drawn portion of the mixing tube forms a small circular passage 59 between it and the upper solid end 60 in the mixing tube.

Within the upper end of the mixing chamber is a butterfly valve 61, mounted upon a shaft 62, which extends outwardly and is provided with an operating lever 63, connected to a rod 64, which extends forwardly and in easy reach of the operator. The butterfly valve 61 has one end beveled at 65, in one direction to fit the outwardly beveled portion 58 of the mixing chamber and the other end beveled in the opposite direction, as indicated at 66 to engage the inwardly beveled wall 57 of the mixing chamber, whereby a tight joint is formed to entirely cut off suction from the intake manifold of the engine. The extreme upper end of the mixing chamber 32 is provided with an annular flange 67, which is adapted to be bolted to the pipe 68 leading to the intake manifold 14.

The lower end of the mixing chamber has formed integral therewith or as an extension of the casting 2, an outwardly extending portion 69 forming the air-intake to the mixing chamber. Secured to the lower face of the portion 69 is a coupling 71, carrying at its upper end a valve seat 72 and a valve 73 resting upon the said seat. The valve 73 is provided with a downwardly extending valve-stem 74, normally held downwardly by a spring 75 and holding the valve 73 upon its seat, as shown in Fig. 1 of the 130

drawings. The coupling 71 has connected at its outer end a flexible tube 76, which is in communication with the exhaust pipe or exhaust manifold, as shown in Fig. 2 of the drawings. The tension of the spring 75 is varied by the screw-cap 77 and is held in its adjusted position by a spring-pressed ball 78 adapted to rest in grooves 79 carried by a cap 77. The suction in the manifold through the mixing chamber unseats the valve 73 and draws a quantity of air or the exhaust from the exhaust-pipe from the engine, as will be hereinafter more fully described.

15 The portion 69 at its upper end is provided with an opening 80, in which is secured a sleeve 81 having a valve seat 82 at its lower end, upon which rests a valve 83 carrying a stem 84, which extends upwardly 20 and is normally held in an outwardly or upwardly position by means of the coiled spring 85. This spring 85 is of greater strength than the spring 75, so that when the engine is running slowly, the valve 83 is held closed and the mixing chamber is only receiving the heated air through the pipe 76. When the engine speeds up the suction through the mixing chamber is greater, which overbalances the tension of 25 the spring 85 and opens the valve 83 and fresh cold air is taken in through the sleeve 81 and mixes with the heated air from the exhaust. In order to vary the tension of the spring 85, I provide a spring-cap 86, 30 working on the spring in the same manner as the cap 76 and held in its adjusted position by means of a ball 87, the same as the ball 78.

A small cylindrical tank 88 is arranged 40 adjacent the engine and is provided with a pipe 89 and connected to a coupling 5 of the gasoline chamber 4. A larger kerosene tank 90 is likewise arranged adjacent the engine and is provided with a pipe 91 connected to 45 the nipple 23, which communicates with the kerosene chamber 21. By this arrangement it will be seen that both the kerosene and the gasoline chambers are in direct communication with the supply tanks.

50 In the form shown in Fig. 3, it has been found very advantageous to heat the mixture or vapor as it passes from the upper end of the mixing chamber 32 and I accomplish this by placing a block 92 between the 55 upper end of the mixing chamber 32 and the pipe 68 leading to the manifold. This, as will be readily seen closes the communication between the pipe 68 and the upper end of the mixing chamber 32. The upper end 60 of the mixing chamber, in the form shown in Fig. 3, has a pipe 93 in communication therewith, which leads around and through the exhaust manifold 94 and extends back and is connected to the pipe 68 at 95 above 65 the block 92. It has been found that the

passage of the vapor or mixture through the exhaust-manifold heats it very intensely so that a more perfect combustible mixture is obtained.

It has also been found advantageous to 70 surround the oil receptacles and the mixing chamber and also the air-intake passage with a water-jacket in order to heat the oil in the oil-chambers and also heat it on its passage to the mixing chamber and nozzle and 75 in order to accomplish this, I have shown the water-jacket entirely surrounding the carbureter, as shown in Fig. 7 of the drawing. A water space 96 surrounds the oil receptacle, which is in communication with 80 the water-space 97 through the passage 98, and said passage being in communication with the water-space 99, surrounding the mixing-chamber 32, through the passage 100. The water is taken into the jacket through 85 the pipe 101 at the upper end of the mixing chamber and circulates therearound and also around the air-intake valves and around the oil receptacle and is discharged through the pipe 102 at the bottom of the oil receptacle. 90

The operation of the device is as follows: When the engine is at rest, as heretofore described, the ball 18 drops upon the ring 19 and the valve 9 is opened so that a quantity of gasoline passes to the chamber 4. An 95 oil-level is maintained within the kerosene chamber 21 by means of the float 24, as heretofore described, and my improved carbureter is shown ready for operation. The starting of the engine causes a suction 100 through the upper end of the mixing chamber and draws the gasoline from the passage 34 out through the opening 38 in the nozzle into the perforated upper end of the mixing tube to the intake-manifold and the 105 engine is started. With the starting of the engine a suction is caused in the manifold 14 and through the pipe 13 the ball 18 is drawn upward upon the seat 17, which prevents the manifold from drawing the gasoline directly from the gasoline chamber 4; the ball being connected to the float the 110 valve is closed and held closed as long as the engine is running. The suction through the mixing chamber, as heretofore described, 115 opens the valve 73 and draws the heated air into the lower end of the mixing chamber and upwardly therethrough on both the inner and outer sides of the mixing tube 50. When it reaches the inwardly drawn portion 120 52 of the mixing tube it shoots across the upper beveled end 49 of the nozzle and draws the gasoline from the opening 48 in the nozzle. At the same time the portion of the air which has passed on the outside of 125 the mixing tube 50, travels inwardly through the openings 56 and causes cross-currents of air with the air and mixture passing through the opening 53 and thoroughly breaking up 130 all vapor particles suspended in the air and

thoroughly mixing the same. The vapor then passes upwardly out of the perforated portion of the mixing chamber and strikes against the inwardly beveled portion 57 of 5 the mixing tube where it is thrown inwardly and is compressed. After it has passed the inwardly beveled portion it is again allowed to expand by the outwardly beveled wall 58 and enters the pipe 68, leading to the intake 10 manifold. This operation continues until all of the gasoline within the chamber 4 has been consumed; the heavier oil or kerosene being not acted upon as long as there is any light oil within the nozzle 33. By the time 15 all of the gasoline is consumed, the engine is heated up and the air taken in through the passage 71 has become thoroughly heated and passes through the mixing chamber, the entire chamber and the nozzle is heated so 20 that the exact operation takes place with the heavier oil.

When the engine is stopped, the ball 18 drops upon the ring 19, allowing the float to descend and open the valve 9, allowing another charge of gasoline to pass to the chamber 4, and the float valve cutting off 25 the supply of gasoline after it has reached a pre-determined level in the chamber. It might be possible to start the engine directly 30 after stopping without the use of gasoline, but to make the device wholly automatic so that there will be no cocks or hand-operating means to fool with, the gasoline supply is renewed whenever the engine 35 is stopped.

This application is a substitute for a prior application Serial #765,322, filed May 3, 1913.

Claims:

40 1. A carbureter comprising a mixing chamber, a light oil supply for said chamber, a heavy oil supply for said chamber, and means controlled by the suction of the engine for cutting off the supply of light oil after the engine is started.

2. A carbureter, comprising a mixing chamber having a light and heavy oil-supply, an automatic means for cutting off the light oil-supply after the engine is started 50 and opening up the supply when the engine is stopped.

3. A carbureter comprising a mixing chamber, an oil supply nozzle extending upwardly from the bottom of the chamber to 55 a point about mid-way its height, a mixing tube within the mixing chamber and spaced from the nozzle and the wall of the mixing chamber and terminating some distance above the lower end of the chamber, said 60 mixing tube having an inwardly contracted portion in a line with the upper end of the nozzle, said tube above the contracted portion having perforations inclined upwardly from the outside, and the upper end of the 65 mixing chamber above the perforated por-

tion of the tube having inwardly inclined walls terminating in outwardly inclined walls, substantially as shown and described.

4. A carbureter comprising a mixing chamber, a light oil-chamber adjacent the 70 mixing chamber and having a heavy oil-chamber surrounding the same, passages leading from the light and heavy oil chambers to the mixing chamber, oil supplies for said chambers and means operated by the 75 suction of the engine for cutting off the light oil-supply after the engine is started.

5. A carbureter, comprising a mixing chamber, a light oil-supply chamber adjacent the mixing chamber, a heavy oil supply surrounding the light oil-supply, supply pipes for said oil chambers, float valves controlling the supply of oil to the said chambers, means operated by the suction of the engine for cutting off the supply of light oil to 80 its chamber, a nozzle extending upwardly within the mixing chamber and having two 85 passages of different sizes in communication with the light and heavy oil chambers, and means for supplying air to the mixing 90 chamber at its lower end.

6. A carbureter, comprising a mixing chamber, an oil-supply nozzle extending upwardly from the lower end of the mixing chamber and having two oil passages of different sizes therethrough, one for light oil and one for heavy oil, a cap on the upper end of the nozzle and having a space between it and the upper end of the nozzle and having a single passage communicating 100 with the space, and means within the nozzle for controlling the supply of heavy oil therethrough.

7. A carbureter, comprising a mixing chamber, an oil supply for the chamber and 105 extending upwardly from the bottom thereof, a mixing tube having a solid lower end surrounding the oil-supply and a perforated upper end above the oil-supply, a butterfly valve within the mixing chamber above 110 the perforated portion of the tube and means for supplying air to the lower end of the mixing chamber on the inside and outside of the mixing tube.

8. A carbureter, comprising a mixing 115 chamber, an oil-supply nozzle extending upwardly from the bottom thereof, a mixing tube having a solid portion surrounding the oil supply and drawn inwardly at the upper end of the oil supply and having a perforated portion of less diameter than the lower portion above the oil supply, the upper end of the mixing chamber above the 120 perforated portion of the mixing tube contracted and then expanded, and means for 125 supplying hot and cold air to the lower end of the mixing chamber on the inside and outside of the tube.

9. A carbureter, comprising a receptacle having light and heavy oil chambers 130

- therein, a mixing chamber in communication with the heavy and light oil chambers, means for supplying heated air to the mixing chamber, a pipe connected to the intake manifold for closing the light oil-supply to the chamber, means for conveying the mixture or vapor from the upper end of the mixing chamber around through the exhaust manifold and discharging it into the intake manifold.
10. A carbureter, comprising a mixing chamber, heavy and light oil-chambers adjacent thereto and in communication therewith, a light and heavy oil-supply for said chambers, a pipe connected to the intake manifold of an engine for closing the supply of light oil to the chambers by the suction in the manifold, and means for supplying the mixing chamber with the exhaust from the engine, and means for heating the vapor or mixture as it passes from the mixing chamber to the intake manifold.
11. A carbureter, comprising a mixing chamber, a light oil chamber, a heavy oil chamber surrounding the light oil chamber, said light and heavy oil chambers being in communication with the mixing chamber, said heavy oil chamber and the mixing chamber having a water jacket surrounding the same and in communication with the water circulation of an engine.
12. A carbureter, comprising a mixing chamber, a light and heavy oil-supply for said chamber, the upper end of said chamber being in communication with the intake manifold, and means caused by the suction
- 5 in the manifold for drawing the exhaust of the engine into the mixing chamber when the engine is running slowly and to draw both the exhaust and fresh cold air when the engine is running fast.
13. A carbureter, comprising a mixing chamber, an oil chamber adjacent the mixing chamber, the upper end of the mixing chamber in communication with the intake manifold, a pipe leading from the exhaust of the engine to the mixing chamber and an auxiliary air-port in communication with the atmosphere, whereby the suction of the engine through the manifold draws the exhaust into the mixing chamber when the engine is running slowly and draws both the exhaust and fresh cold air when the engine is running fast.
14. A carbureter comprising a mixing chamber, an oil-supply nozzle extending upwardly from the lower end of the mixing chamber and having two oil-passages of different sizes therethrough, one for the light oil and one for heavy oil, a cap on the upper end of the nozzle and having a space between it and the upper end of the nozzle and having a single passage communicating with the space of a diameter less than that of the heavy and light oil-passages.
- Signed by me, this 11th day of August, 1915.

ANTHONY COSTA.
